SPARK GAP

William R. Baker, Berkeley, Calif., assignor to the United States of America as represented by the United States Atomic Energy Commission

Application July 14, 1954, Serial No. 443,448

5 Claims. (Cl. 317—31)

The present invention relates to a spark gap and, more particularly, to an electrical protective device and circuit for a radio-frequency transmission line.

It has been found that known protective devices, such as spark gaps mounted within gas-filled envelopes, are inadequate in the high voltage, high-frequency field because the operation thereof is too slow and, further, such devices cannot withstand the overload conditions which occur. Also, the known types of such devices generally become a part of the system to be protected and add undesirable factors which may alter the wave form of the voltage to an extent that corrective measures are necessary. The required corrective measures often lower the efficiency of the system.

The present invention overcomes the foregoing disadvantages by providing a protective device which is connected into the system at a minimum voltage node. A direct current control voltage having a value below the continuous discharge value for the device is impressed between two spaced-apart electrodes. It has been found that a fault results in a change of the voltage at the node so that a small increase in the radio-frequency voltage at the protective device results in a low resistance path for the direct current to spark over. The surge in the direct current is then utilized to disable the radio-frequency power connection to the system.

It is therefore an object of the invention to provide a new and improved spark gap device.

Another object of the invention is to provide a high speed protective system for a radio-frequency transmission line circuit.

A further object of the invention is to provide a spark gap device to be connected into a radio-frequency transmission line at a minimum voltage node of the standing wave of voltage.

A still further object of the invention is to provide a low-resistance path for a control current upon a fault in the radio-frequency circuit.

Still another object of the invention is to provide a spark-gap device having an impressed control voltage below the spark level for installation at a minimum node on a radio-frequency transmission line.

Other objects and advantages of the invention will be apparent in the following description and claims considered together with the accompanying drawing, in which:

Figure 1 is a view of the spark gap, partly in section, as installed; and

Figure 2 is a schematic wiring diagram of a circuit incorporating the spark gap of Fig. 1.

Referring to the drawing in detail, Fig. 1 in particular, there is provided a coaxial transmission line 11, illustrated partially and in cross section. Such transmission line 11 has a center conductor 12 and an outer conductor 13, the latter having an aperture 14. A mushroom-shaped first electrode 15 is suitably mounted, as by a screw 16 on the center conductor 12, in alignment with the aperture 14.

2

Centrally disposed within the aperture 14 is a hollow second electrode 17 having a semi-spherical portion 18 extended toward and spaced from the first electrode. To maintain the position of the second electrode 17 such electrode is suitably mounted within an open-ended housing 21 which engages the outer conductor 13 as by threads 22. It is to be noted that a good electrical connection should be provided between the housing 21 and the second electrode 17 so that the latter provides electrical continuation of the former.

A third rod electrode 26 is disposed coaxially within the hollow second electrode 17 and extends through an opening 27 in the semi-spherical portion 18 of the latter. It is to be noted that the opening 27 should be larger than the third electrode 26 to provide insulating space therebetween and that the extended end of the third electrode is rounded. The mounting of the third electrode 26 in the second electrode 17 may be accomplished in any conventional manner to provide suitable insulation between the two electrodes. A conductor 28 is connected at one end to the third electrode 26 and is extended transversely thereof through an aperture 29 in the second electrode 17 to an electrical receptacle 31 suitably mounted in the wall of the housing 21.

In the illustration of the drawing, see Fig. 2, there is provided a conventional high-power and high-frequency oscillator 36 having a power input 37 connected to a suitable source 38 of energizing power. One of the connections 39 between the source 38 and the input 37 includes 30 a normally closed contactor 41 of a conventional high speed relay 42. One of the output terminals 43 of the oscillator 36 is connected to ground and the other terminal 44 is connected to the center conductor 12 of the transmission line 11. Thus, by connecting the outer conductor 13 of the line 11 to ground and connecting the center conductor 12 at the extended end of the line to a coupling loop 45, which extends into a cavity resonator load 46 and is grounded at a wall of the resonator, power is transmitted from the oscillator 36 to the load 46. At 40 a point on the transmission line 11 where the standing wave of the radio-frequency voltage is at a minimum node, as indicated by the diagram 51 of Fig. 2, the three electrodes 15, 17, and 26 of the spark gap arrangement are installed in accordance with the foregoing description.

45 Now, in accordance with the invention, there is provided a conventional direct current power supply 56 having a grounded positive terminal 57 and a negative terminal 58. A radio-frequency choke coil 61 is connected from the negative terminal 58 to the third electrode 26 of the spark gap to protect the power supply 56 from voltage surges and to prevent the radio-frequency voltage of the transmission line from affecting the power supply. Voltage variations at the junction between the choke coil 61 and third electrode 26 are coupled to the 50 input of an amplifier 62 by a capacitor 63 connected therebetween. The coil of the relay 42 is connected across the output of the amplifier 62. Thus, it is seen that the voltage of the power supply 56 appears between the first and third electrodes 15 and 26 of the spark gap and also between the second and third electrodes 17, 26 so that any current flowing between such pair of electrodes will develop a voltage at the input of the amplifier 62 which, in turn, results in operation of the relay 42 to open the input circuit of the oscillator 36.

55 Having thus described the elements of the invention in detail, the operation will now be described. With the direct current power supply 56 suitably energized, a unidirectional voltage appears between the first and third electrodes 15, 26 and between the second and third electrodes 17, 26. Proper adjustment of the gap between such electrodes 15, 26 and of the value of the unidirectional voltage applied will prevent a flow of direct current.

The contactor 41 of the relay 42 remains in a closed condition when there is no excitation of the coil. Thus, the output voltage of the radio-frequency oscillator 36 appears at the input end of the transmission line 11. A standing wave of voltage appears along the transmission line 11 with a minimum voltage node occurring at the position of the spark gap elements. As long as the voltage at such node remains at such minimum value, or lower, there will be no direct current flow from the power supply 56.

Now, upon the occurrence of a fault in the radio-frequency circuit the standing wave voltage distribution is disturbed so that an increasing voltage appears at the former minimum voltage node position. Because of the small gap between the first and second electrodes 15, 17, the increasing voltage therebetween soon reaches the breakdown value of the gap and a spark occurs. The arc thus established by the radio-frequency voltage provides a low-resistance path for the direct current between the first and third electrodes 15, 26. The flow of direct current between such electrodes 15, 26 results in a voltage drop across the choke coil 61 and in a voltage change at the junction of the coil and third electrode being coupled to the input of the amplifier 62. The output of the amplifier 62 then energizes the coil of the relay 42 to open the contactor 41. The input to the radio-frequency oscillator 36 is then broken and the radio-frequency voltage of the transmission line 11 becomes zero.

The foregoing operation at the time of a radio-frequency fault is substantially instantaneous (in the order of a few microseconds) with the occurrence of the fault. While the relay 42 has been illustrated in the output circuit of the amplifier 62, such relay could readily be connected to operate in the connection between the third electrode 26 and the terminal 58 of the power supply 56.

It is to be noted that the spark gap device of the present invention comprises two coaxial electrodes 17, 26 facing a larger electrode 15, thus providing an air gap between the coaxial electrodes as well as two separate voltage gaps between the electrodes 15, 17 and 15, 26. The air gap between the coaxial electrodes 17, 26 separates the spark due to radio-frequency current and the spark due to direct current so as to reduce the intensity of the arc over the intensity where only two electrodes are used. Also, the duration of the spark is reduced. Such advantages result from the fact that once a spark-over to the first electrode 15 has occurred there is sufficient ionization in the gap between the second and third electrodes 17 and 26 to cause a secondary spark which short-circuits the direct current power supply 56 thereby extinguishing the spark between the first and third electrodes 15, 26 because of the direct power supply to provide protection from sparking damage to the transmission line.

It has been found, for example, that for a radio-frequency voltage range from 16KV to 29KV suitable spark gap settings between $\frac{3}{16}$ inch and $\frac{1}{2}$ inch are satisfactory. With such gap settings the direct current bias between the first and third electrodes 15, 26 may be established between 800 volts and 1000 volts for satisfactory operation.

While the salient features of the present invention have been described in detail with respect to a single embodiment, it will be apparent that numerous modifications may be made within the spirit and scope of the invention,

and it is therefore not desired to limit the invention to the exact details shown except insofar as they may be defined in the following claims.

What is claimed is:

- 5 1. In a spark gap device for installation on a two-conductor transmission line having a high-frequency standing wave voltage distribution, the combination comprising a first electrode mounted on one conductor of said line at a voltage node, a second hollow electrode mounted
- 10 10 on the other conductor of said line in alignment with said first electrode, said first and second electrodes spaced apart a predetermined distance, a third electrode mounted coaxially within said second electrode and extended through an opening therein, and means connected between said one conductor and said third electrode and between said second and third electrodes for applying a direct current having a value below the continuous discharge value.
- 15 2. In an electrical protective device, the combination comprising a first and second electrode disposed in spaced-apart relation and respectively connected across a source of high voltage having a high frequency, a third electrode mounted coaxially within said second electrode and extended through an opening therein, and direct current means connected between said first and third electrodes and between said second and third electrodes.
- 20 25 3. In an electrical protective device, the combination comprising a first and second electrode disposed in alignment and in spaced apart relation, a high voltage and high-frequency source respectively connected to said first and second electrodes, a third electrode disposed coaxially within said second electrode in insulated relation and having an end thereof extended through an opening in said second electrode, and direct current means connected between said first and said second electrodes and between said second and third electrodes.
- 30 35 4. The combination of claim 3 wherein said first electrode is spaced apart from said second and third electrodes by a gap length greater than the continuous discharge gap length at the values of high frequency and direct current voltages.
- 40 5. In a spark gap device for installation on a coaxial transmission line system having a high-frequency standing wave voltage distribution, the combination comprising a 45 button-type first electrode disposed in electrical contact on the center conductor of said coaxial transmission line at a voltage node of said standing wave voltage, a hollow and tubular second electrode disposed through and in electrical contact with the outer conductor of said coaxial transmission line and aligned with said first electrode, an elongated third electrode mounted coaxially in and insulated from said second electrode with one end extended through an opening in said second electrode toward said first electrode, and a direct current source connected between said first and second electrodes and between said second and third electrodes.
